UNITED STATES PATENT OFFICE.

WILLIAM S. HOOD, OF SAN ANTONIO, TEXAS, ASSIGNOR, BY MESNE ASSIGNMENTS, TO
P. G. CALDWELL, OF SAN ANTONIO, TEXAS.

VALVE-GRINDING IMPLEMENT.

1,413,273.

Specification of Letters Patent. Patented Apr. 18, 1922.

Application filed March 20, 1919, Serial No. 283,736. Renewed March 14, 1922. Serial No. 543,744.

To all whom it may concern:

Be it known that I, WILLIAM S. HOOD, a citizen of the United States, residing at San Antonio, in the county of Bexar and 5 State of Texas, have invented certain new and useful Improvements in Valve-Grinding Implements, of which the following is a specification.

The present invention relates to means 10 for rotating the valves of internal combustion engines and the like when the same are being ground to effect a proper seating action.

The primary object is to provide an implement of this character that is not only simple, but highly effective, and is applicable to practically any type of engine or motor and to the different types of valves employed therein.

20 A further and important object is to provide a device that will secure what has been found to be the most satisfactory movement of the valve without undue pressure on such valve, the device moreover being 25 such that it can be satisfactorily operated by a comparatively unskilled person.

In the accompanying drawing:—

Figure 1 is a vertical sectional view through the preferred embodiment of the 30 invention.

Figure 2 is a detail view through the lower portion of the shaft and the valve engaging element at right angles to Figure 1.

35 Figure 3 is a detail view of the valve engaging element alone.

Similar reference numerals designate corresponding parts in all the figures of the drawings.

40 In the embodiment illustrated a base is employed that is adapted to be placed upon the engine around the valve and will extend over the same. This base preferably consists of a ring 4 that rests upon the 45 face of the engine wall and is provided with upstanding spider arms 5 supporting a central bearing element 6 having an axial bore 7. The base is preferably a single-piece casting and is of sufficient weight to rest 50 firmly in position.

Journalized in the element 6 of said base is a shaft 8, the inner end of which is slotted, as shown at 9 to receive a reversible valve engaging element in the form of a blade 10. 55 One end of the blade is provided with

spaced spurs or prongs 11 adapted to engage in the spaced openings or sockets formed in one well known form of valve. The opposite end of said valve is provided with a curved tapered edge 12 that is 60 adapted to engage in the transverse slot formed in another type of valve. The blade is secured to the shaft in either of its reverse positions by a suitable transverse holding bolt 13.

Secured to the shaft 8 by a set screw 14 or other suitable device is a balance or fly wheel 15 that is thus adjustable along the shaft, and this fly wheel constitutes, with the outer end of the bearing element 6, a thrust 70 bearing for said shaft. Preferably a ball bearing 16 is interposed between the hub of the fly wheel and the element 6, the latter being provided with a recessed seat 17 that receives a bearing disk 18, and the fly wheel 75 having a recess 19, the bottom surface of which is borne against by the balls.

For the purpose of operating the shaft an actuating bar 20 is employed having a central opening 21 that receives the outer 80 portion of the shaft, said bar being thus longitudinally slidable upon said shaft. A flexible cord element 22, preferably a thong of raw-hide or leather, has its ends passed through openings 23 in the ends of the bar 20 and knotted as shown at 24. This thong also passes through one of a plurality of openings 25 formed in the outer portion of the shaft 8 at different distances from its outer end.

90 The manner in which the implement is used may be briefly outlined as follows. Assuming that the outer face of the valve to be ground is substantially flush with the adjacent surrounding surface, the ring 95 4 is placed upon said surface, so that the center of the valve is in axial line with the shaft 8. The set screw 14 is then loosened and the shaft moved inwardly until the blade 10 is engaged with the valve the 100 proper end of said blade being of course placed in operative position. When so engaged the set screw 14 is again tightened. To rotate the valve, therefore, it is only necessary to reciprocate the bar 20, first 105 giving a slight rotation to the shaft 8. The said shaft will thereupon be caused to rotate, causing the thong to wrap upon and be unwrapped from the shaft in a manner well understood, and effecting the succes- 110

22
sive rotation of the shaft in opposite directions. The longitudinal movement of the actuating bar and the strain transmitted to the shaft will cause said shaft to have an 5 end thrust, but as will be evident, this is taken by the thrust bearing and the valve is relieved from the same. Consequently no undue pressure will be exerted upon said valve, though sufficient pressure can be 10 obtained by a proper adjustment of the balance wheel 15 to secure the most effective grinding action. In case the valve is within the engine head, the ring 4 is seated upon the outer face of the head and the 15 shaft is moved inwardly sufficiently to engage the internal valve. In that case it is preferable to engage the flexible element 22 in the outermost opening 25, so as to properly space the actuating bar 20 from the fly wheel.

From the foregoing, it is thought that the construction, operation and many advantages of the herein described invention, will be apparent to those skilled in the art without further description, and it will be understood that various changes in the size, shape, proportion and minor details of construction may be resorted to without departing from the spirit or sacrificing any of the advantages of the invention.

Having thus described my invention, what I claim as new, and desire to secure by Letters Patent, is:—

1. In a valve grinding implement, the 35 combination with a supporting base adapted to extend over a valve, of a shaft journaled in the base, means on the inner end of the shaft for detachably engaging directly with the valve, an actuating device mounted to 40 move longitudinally on the outer portion of the shaft, a flexible connection between the actuating device and shaft that wraps directly upon the latter for effecting the rotation of the same on the reciprocation of the 45 actuating device, and a fly wheel carried by the shaft and constituting a thrust bearing therefor on the base to prevent undue longitudinal movement of said shaft and consequent undue pressure upon the valve when 50 the actuating device is operated.

2. In a valve grinding implement, the 55 combination with a supporting base adapted to extend over a valve, of a shaft journaled in the base, means on the inner end of the shaft for detachably engaging directly with the valve, an actuating device mounted to move longitudinally on the outer portion of the shaft, a flexible connection between the actuating device and shaft that wraps directly upon the latter for effecting the rotation of the same on the reciprocation of the 60 actuating device, a fly wheel carried by the

shaft and constituting a thrust bearing therefor on the base to prevent undue longitudinal movement of said shaft and consequent undue pressure upon the valve when the actuating device is operated, and means for adjustably securing the fly wheel to the shaft at different points to permit the proper engagement of the valve engaging means 70 with the valve and an effective grinding pressure upon said valve.

3. In a valve grinding implement, the combination with a supporting base comprising a ring, upstanding spider arms carried thereby and a bearing element supported by the spider arms, said ring being adapted to surround a valve to be ground, of a shaft journaled in the bearing element and projecting within the spider, a valve 80 engaging member carried by the inner end of the shaft, a fly wheel mounted on the shaft, means for fixing the fly wheel at different points along the shaft, a ball bearing interposed between the fly wheel and the 85 bearing element and borne against by the fly wheel, and means carried by the outer portion of the shaft for effecting the rotation of said shaft successively in opposite directions.

4. In a valve grinding implement, the combination with a base adapted to be placed over a valve, of a shaft journaled therein, a valve engaging element carried by the inner end of the shaft, a thrust bearing 95 between the shaft and base to prevent undue longitudinal movement of the shaft, said thrust bearing being adjustable to permit the longitudinal adjustment of the shaft in the base, an actuating device slideable on the 100 shaft, a flexible member connected to the actuating device, and means for engaging said flexible member at different points on the outer portion of the shaft.

5. In a valve grinding implement, the 105 combination with a base adapted to be placed over a valve, of a shaft journaled therein, a valve engaging element carried by the inner end of the shaft, a thrust bearing between the shaft and base to prevent 110 undue longitudinal movement of the shaft, said thrust bearing being adjustable to permit the longitudinal adjustment of the shaft in the base, an actuating bar slideable on the outer portion of the shaft, and a flexible 115 cord member having its ends connected to the ends of the bar, said shaft having openings at different distances from its outer end through which the cord is adapted to be passed.

In testimony whereof, I affix my signature.

WILLIAM S. HOOD.
